[57] CLAIM

The ornamental design for a tape gun belt, as shown and described.

DESCRIPTION

FIG. 1 is a front perspective view of a tape gun belt showing my new design;

FIG. 2 is a rear perspective view thereof;

FIG. 3 is a right side elevation view thereof, the left side elevation view being identical;

FIG. 4 is a top plan view thereof;

FIG. 5 is a bottom plan view thereof; and,

FIG. 6 is a front perspective view thereof. The tape gun and tools shown in "dotted lines" are inserted for illustration purposes only. These items are in no way to be construed as part of the overall tape gun belt for design patent purposes.
